UNITED STATES PATENT OFFICE.

HAROLD CHARLES AND IVERN ANTHONY JACOBS, OF LEEDERVILLE, NEAR PERTH,
WESTERN AUSTRALIA, AUSTRALIA.

MACHINE FOR DISPENSING BEVERAGES FROM THE BULK.

Application filed March 23, 1923. Serial No. 627,162.

To all whom it may concern:

Be it known that we, HAROLD CHARLES and IVERN ANTHONY JACOBS, both subjects of the King of Great Britain, residing at 5 Leederville, near Perth, Western Australia, Commonwealth of Australia, have invented certain new and useful Improvements in Machines for Dispensing Beverages from the Bulk, of which the following is a specification.

This invention provides a compact and easily manipulated machine adapted to be fitted on a bracket or counter for the dispensing of beverages from the bulk and it 15 comprises means whereby any predetermined flavouring essence or syrup may be concurrently added in any ratio or degree to the volume of soda water of the beverage.

The dispensing of the different beverages is effected by the same working handle 20 which operates in common in respect of the soda water and different syrups. This handle has a threefold action and function. Firstly—By its radial movement on its 25 pivotal stem it is enabled to be brought into operative contact with any one of the push down rods for the opening of the syrup valves.

Secondly—It possesses a lifting movement 30 by a down pressing contact against an adjustable fulcrum member, whose position determines the degree of opening of the syrup valves and said movement opens the syrup valve and also the outlet valve for the dispensing of soda water in the form of a 35 hollow stream into the drinking glass concurrent with the syrup. Thirdly—Such lifting movement reduces and restricts the flow of the soda water from its high pressure storage chamber to an intermediate and 40 central reception chamber in order to avoid flooding and waste during the dispensing of the beverage.

The construction and use of these and 45 other features will be explained with the aid of the attached drawings wherein Fig. 1 is a sectional elevation showing the machine in its idle position the inlet for the soda water being fully open for the free flow of 50 same from its high pressure storage chamber to the intermediate or reception chamber the soda water and syrup outlet valves being closed. Fig. 2 is a similar view but showing the machine in its active position the soda

water and syrup outlet valves being open 55 while the soda admission pipe is partially closed in order to reduce and restrict the flow and consequent pressure in the reception chamber during the dispensing of the beverage.

Fig. 3 is an overhead plan view—for sake of clearness certain of the syrup compartments are broken away and their cover and working handle and members are removed— 60 this view shows the disposition and arrangement of said compartments and their outlet valves in the shape of an arc thereby enabling said compartments to be wedge or tapered on plan. Fig. 4 and Fig. 5 are 65 respective plan and elevation of the swivel head for connecting the working handle to its pivotal stem.

Fig. 6 is an enlarged sectional elevation 70 of a syrup valve and its members.

Referring to said drawings the machine 75 comprises a central chamber *a* which acts as an intermediate or reception chamber for the soda water whose normal level is indicated at *a* said chamber *a* being in free and open communication with and fed from a 80 high pressure storage chamber from which latter the soda water is fed by pipe *a*¹.

This chamber *a* by its top overhang web *a*² is secured to the bracket *a*³ of the plurality of syrup compartments *b* which are 85 also held on their base plate *b*¹ by the retaining screw studs *b*² as seen in Figs. 1 and 3. Within said chamber *a*, vertical pivotal stem *c* is housed being tight sealed by stuffing box *c*¹ made integral with the chamber 90 *a* and having gland *c*². On said stem *c* is coiled a spring *c*³ operating between its nestling thimble *c*⁴ and the lower end of said stuffing box *c*¹, the purpose of said spring being 95 to urge and return said pivotal stem *c* and thereon carried soda water outlet valve *d* to the idle position as soon as the beverage is dispensed as seen in Fig. 1. This soda water outlet valve *d* is of conical form as seen in Figs. 1 and 2 and interscrews on 100 said pivotal stem *c* and is preferably made of rubber or like composition.

This valve *d* neatly makes seating contact with the soda water outlet *e* which interscrews into the bottom of the chamber *a*.

This outlet member *e* is formed with radial inlet ports *e*¹ in order to further soften 105 the outflow of the soda water.

The stem *c* at its head is made with a reduced portion *c*⁴ which projects through an aperture in the swivel head *f* and is made secure by lock nut *f*¹, said head made with the upstanding cheeks *f*² on which by cross pin *f*³ the working handle *g* is pivotally and radially carried as shown clearly in Figs. 1, 2, 4 and 5.

By means of said swivel head *f* the handle *g* is enabled to have a radial movement and to be brought into operative contact with any one of the push down rods *h* for operating the outlet valves *k*¹ of the syrup compartments *b* and also makes contact with the fulcrum *j* for opening the soda water outlet valve *e*. When it is desired to dispense soda water only the handle *g* is brought into operative contact with the centrally positioned and fixed fulcrum *y*—see Fig. 4.

The angularly and vertically movable stem *c* is formed with a circular groove *h*² which registers with the outlet of the soda water feed pipe *a*¹ for the opening and partial closure of same.

The terminal *g*¹ of the handle *g* is formed with a guiding groove *j*¹ wherein it makes downwardly pressing and sliding contact with the head of any one of said push down rods *h* for actuating the opening of the syrup valves, said rods being arranged in a parallel row corresponding with the arc line of the syrup compartments *b* so as to be conveniently operated by the common handle *g*. These push down rods *h* are guidably held in the sleeves *j* which inter-screw in the web *a*² of the central chamber *a* and whereby said sleeves *j* act as vertically adjustable limits for the down movement of the working handle *g* and consequent lift of the stem *c* and also obviate any excess of strain being imparted to the push rods *h* also determine by their alterable position the degree of opening of the syrup valves *k*¹ and soda water outlet valve *e*. These push rods *h* at their lower ends downwardly engage against one end *m* of a double ended rocker arm pivoted at *m*¹ to a bracket *m*² secured to the plate *m*³ which latter by stud pins *m*⁴ is secured to the base of the central chamber *a*, the opposite end *m*⁵ of said arm is adapted to make upwardly pressing contact against the stem *n* of the syrup valve *k*¹. Said stem *n* works in stuffing box *n*¹ made integral with the syrup compartment *b*.

These syrup valves *k*¹ are of an overhang form and type as clearly seen in Fig. 6. Their valve stems *n* are fitted with coiled spring *n*² operating between the adjustment nut *n*³ and the stuffing box *n*¹, the duty of said spring being to return the valves *k*¹ to their closed position immediately the pressure is removed by the handle *g* from the head of the push down rods *h*.

The syrup outlet *p* by pipe *p*¹ leads the

syrup closely adjacent to the soda water outlet *e*, as seen in Figs. 1 and 2 for dispensing into a glass or like vessel.

The operation of the machine may be briefly described:—

For the dispensing of a beverage of a desired flavor the handle *g* is moved on its pivot stem *c* to the proper position for operative contact with the push down rod *h* of the compartment as *b* containing the syrup having such desired flavor. The handle *g* is now upwardly moved on its pivot *f*³ thus bringing its terminal *g*¹ into pressing contact with the head of said push down rod *h* thereby partially opening outlet valve *k*¹ of said syrup compartment *b* while by the continued upward movement of said handle *g* its terminal *g*¹ is brought into pressing contact with the limit stop *j* which also acts as a fulcrum for said handle *g* causing the pivotal stem *c* to lift and open the soda water outlet valve *e* and to complete the opening of the syrup valve *k*¹ for the dispensing of the beverage.

What we claim as our invention and desire to secure by Letters Patent is:—

1. In an apparatus for dispensing beverages, a chamber, a stem slidably mounted therein, an outlet valve controlled by the sliding movement of said stem, a head pivoted to the stem and an arm extending therefrom, a plurality of syrup compartments having dispensing outlets, valves controlling the flow of liquid through the outlets of said compartments, and a plurality of controlling means for said last named valves arranged on an arc of a circle and within reach of said arm.

2. In an apparatus for dispensing beverages, a chamber, a stem rotatably and slidably mounted therein, an outlet valve controlled by the sliding movement of said stem, means for limiting the sliding movement of said stem, a head pivoted to the stem and an arm extending therefrom, a plurality of syrup compartments having dispensing pipes leading therefrom to a point adjacent the first named outlet valve, outlet valves controlling the flow of liquid through said pipes, and a plurality of controlling means for said last named valves arranged on an arc of a circle and within reach of said arm.

3. In an apparatus for dispensing beverages, a centrally positioned chamber for dispensing carbonated water at low pressure, a plurality of syrup compartments positioned on the arc of a circle about said chamber, a valve governed outlet leading from said chamber, and valve controlled conduits leading from said compartments to a position adjacent said outlet, a stem mounted for rotary and longitudinal movement in said chamber and adapted to control the valve in the outlet thereof, said cham-

ber having an inlet passage and said stem having a circular groove adapted to be brought into alignment with said inlet passage, a spiral spring for holding said stem in normal position, an arm pivoted to said stem adapted to contact with and selectively operate the outlet valves of said compartments.

4. In an apparatus of the character described, a chamber for carbonated liquid, an outlet leading therefrom, a plurality of compartments having outlets, valves controlling said outlets, resilient means for holding said valves normally closed, vertically movable rods for controlling the valves of said compartments arranged on the arc of a circle, a radially and vertically movable stem controlling the valve of said chamber, a handle pivotally attached to said stem for movement in a vertical plane and adapted to contact selectively with any one of said rods.

5. In an apparatus of the character described, a chamber for containing carbonated liquid under pressure, an inlet and outlet passage for said chamber, a stem vertically and radially movable in said chamber, said stem being adapted to partially close said inlet passages and open said outlet valve simultaneously, compartments having valve controlled outlet passages, vertically movable rods adapted to operate said last named valves, a handle pivoted to said stem having a terminal adapted to be brought selectively to position upon said rods, whereby said stem and

one of said rods may be selectively operated by a single movement of said handle.

6. In a device of the character described, a chamber for carbonaceous liquid having an outlet, syrup compartments, said syrup compartments having outlet pipes leading therefrom to a position adjacent soda-water outlet, overhung valves controlling the outlets from said compartments, springs holding said valves normally closed, a valve for said soda-water outlet, means for controlling said compartment valves arranged on the arc of a circle, and a common means for operating the valve of the soda-water outlet and simultaneously operating anyone of said compartment valves.

7. In a device of the character described, a chamber for containing carbonaceous liquid, compartments for syrup or the like, outlet conduits for said chamber and compartments and valves controlling said conduits, means for normally holding said valves closed, and means connected with the valve of the chamber adapted to selectively open a valve of anyone of said compartments simultaneously with the valve of said chamber by a lifting of said means.

In testimony whereof we have hereunto set our hands in the presence of two subscribing witnesses.

HAROLD CHARLES.
IVERN ANTHONY JACOBS.
